LEWIS B. DOMAN, OF EAST SYRACUSE, NEW YORK.

AIR-COOLING SYSTEM FOR INTERNAL-COMBUSTION ENGINES.

Application filed November 28, 1916. Serial No. 133,943.

To all whom it may concern:

Be it known that I, LEWIS B. DOMAN, a citizen of the United States of America, and resident of East Syracuse, in the county of 5 Onondaga, in the State of New York, have invented new and useful Improvements in Air-Cooling Systems for Internal-Combustion Engines, of which the following, taken in connection with the accompanying draw- 10 ings, is a full, clear, and exact description.

This invention relates to certain improvements in air cooling systems for internal combustion engines, as commonly used in motor vehicles, and refers more particularly 15 to the means for automatically controlling the circulation of air through the radiator and around the cylinder of the water-cooled engine.

It is obvious, however, that the same or 20 equivalent apparatus may be used in connection with any internal combustion engine which is cooled solely by the circulation of air around the cylinder.

It is well understood that internal combustion engines, such as are used in automobiles, perform at their highest fuel efficiency 25 when the cylinder walls are kept at or near a certain temperature;—this is usually about 180° F. However, as heretofore constructed 30 automobiles have necessarily been supplied with radiators or other cooling media of sufficient capacity to prevent overheating when operated in summer temperatures, which capacity was much too great (for 35 proper efficiency and operation) when the car was operated under cold or winter conditions.

In the use of the combined water and air cooling systems, most commonly employed 40 in motor vehicles of this type in cold climates, there is always more or less danger of freezing the cooling liquid in the radiator, particularly when the engine is started cold and immediately driven into a freezing tem- 45 perature, due to the rapidity of flow of the frost-laden air around the thin walls of the radiator and jacket of the cylinders, thereby stopping the circulation and frequently resulting in leakage or more serious injury to 50 the radiator or engine and their connecting parts.

Furthermore, even though the cooling liquid may be free to flow through the entire circulating system and the engine and 55 radiator are sufficiently warm to prevent

freezing of such liquid for a short period of time in extremely cold weather, if the engine is stopped for any considerable period of time and the frost-laden air is free to flow through the radiator, the temperature of the 60 liquid therein is soon reduced to the freezing point with the same dangerous results, to say nothing of the inconvenience and annoyance to the operator.

I am aware that thermo-controlled devices 65 have been used to vary the speed of circulation of the cooling water in some automobile motors, but these have been of such design as to vary or stop circulation through the radiators, which allow the radiator to 70 freeze even more quickly than would be the case if the water were allowed free circulation. By placing the air-controlling means outside the radiator and allowing free circulation of the water, but controlling the supply of air, this very serious objection is 75 overcome.

The primary object, therefore, of my present invention is to provide means controlled by the temperature of the engine or 80 other part of the circulating system for automatically controlling the circulation of air through the passages in the radiator or other passages leading to the interior of the hood usually provided for air-cooling purposes, 85 so that when the engine is cold or until it rises to a certain temperature, these passages will be closed and when the temperature rises above such predetermined degree, the 90 passages will be automatically opened.

Another object is to utilize the suction produced by the operation of the engine pistons for opening the shutters or closures for the air-circulating passages.

Other objects and uses will be brought out 95 in the following description.

In the drawings—

Figure 1 is a side elevation of a portion of an internal combustion engine and radiator showing one form of my improved air-cooling apparatus applied thereto, a portion of said apparatus and a part of the intake manifold of the engine being shown in section and the shutters in their closed positions.

Figure 2 is a front end view of the radiator and adjacent portion of the same air-controlling apparatus.

As illustrated, this air-controlling apparatus comprises a series of blind-shutters 110

—1— arranged horizontally one above the other and hinged at their upper edges at —2— to the front face of the radiator, as —A—, and of sufficient combined area to 6 cover the entire system of air-circulating passages therethrough when closed.

The lower edge of the lower shutter is arranged to fold directly against the front face of the radiator, while the lower edges 10 of the superposed shutters are arranged to overlap upon the front faces of the upper edges of the adjacent shutters, thereby effectively closing the system of air passages through the radiator.

15 All of the shutters are connected for simultaneous movement by providing their lower edges with outstanding arms —3— which are pivotally connected to upright link or operating bar —4—.

20 The lower end of this bar is pivotally connected to one arm —5— of a bell-crank lever —6—, the other arm —7— of which is pivotally connected to a piston rod —8— of a piston —9— which is movable in a cylinder —10— for operating the lever —5— 25 to open the shutters in a manner hereinafter described.

These shutters are normally and automatically closed by means of a spring 30 —11— having one end connected to a radial arm —12— on the bell-crank lever —6— and its other end connected to a lug —13— on the cylinder —10—.

35 A pipe —14— is connected at one end to the cylinder —10— and has its other end provided with branches —15— and —16—, the branch —15— being connected to a relatively small opening —17— in one end of an intake manifold —18— of an internal 40 combustion engine —B—, while the other branch —16— is normally open to the atmosphere, but is adapted to be closed by a temperature-controlled valve —19—.

45 As illustrated, this valve is mounted on one end of a thermal bar —20— having its other end secured to a suitable support —21— on the engine, the intermediate portion being provided with an adjusting screw —22— by which the valve —19— may be 50 adjusted relatively to the open end of the branch —16—.

The thermal bar —20— is located within the sphere of heat of the engine or water jacket of the cylinder as forming a part of the circulating system, and it is arranged 55 so as to normally hold the valve —19— open, while the engine and cooling medium is cold and until the temperature is sufficiently high to require the free flow of the cooling air.

60 While the valve is in its open position, it is evident that the suction in the intake manifold —18— will simply draw the air through the open end of the branch —16— and thence through the branch —15— into

said intake without affecting the operation of the piston —9—.

On the other hand, after the engine has been running some time, the heat developed thereby will be transmitted to the thermal bar —20— which, in turn, will be affected in such manner as to close the valve —19— against the open end of the branch —16—, thereby closing communication between the intake manifold —18— and atmosphere and causing a sufficient degree of suction in the pipe —14— and adjacent end of the cylinder —10— to operate the piston —9— for opening the shutters —1— through the medium of the lever —6— and upright bar —4— against the action of the retracting spring —11—.

The piston and shutters will be held in such position as long as the engine is in operation, and the temperature is such as to hold the thermally-operated valve —19— closed.

Under these conditions, the shutters will be kept open to allow free circulation of the cooling air through the radiator and around the cylinders of the engine, which circulation may be accelerated by the usual fan, not shown.

Immediately upon stoppage of the engine, the suction in the cylinder —10— will cease and the spring —11— will instantly close the shutters, thereby preventing the circulation of air through the radiator and around the engine, and enabling the heated liquid in the circulating system to maintain its high temperature for a much longer period of time than would be possible if the passages through the radiator were left open.

Again, if, while the engine is still operating with the shutters open and the temperature of the liquid in the circulating system should be lowered by the inflowing air to such a degree as to restore the thermal bar —20— and its valve —19— to their normal open positions, the spring —11— would then close the shutters and hold them closed until the temperature again rose to a sufficient degree to close the valve —19— and cause the opening of the shutters.

It is, therefore, apparent that the operation of the shutters is rendered entirely automatic by the thermally-controlled valve.

It is evident, however, that any other equivalent thermally-controlled device for operating the shutters may be substituted for that shown without departing from the spirit of my invention.

What I claim is:

1. The combination of an internal combustion engine, a cooling system therefor, means for varying the capacity of the cooling system, a motor for actuating the capacity-varying means, having a chamber connected with the intake of the engine, a port connecting this chamber with the at-

mosphere, and thermostatic means adapted to close the port, thereby controlling the degree of vacuum in said chamber.

2. The combination of an internal combustion engine, a cooling system therefor, including a radiator, means including a shutter for varying the cooling capacity of said radiator, a motor actuated by suction produced by the action of the engine for operating the shutter, a port connecting the motor with the atmosphere to partially neutralize the effect of the suction acting thereon and a thermostatically controlled valve cooperating with said port to control the degree of suction acting upon the motor.

3. The combination of an internal combustion engine, a cooling system therefor, including a radiator, means including a self-

closing shutter cooperating with the radiator for varying the capacity of the cooling system, a piston motor for actuating said shutter, means actuated by the engine for producing a partial vacuum in the piston chamber for operating the motor to open the shutter, a port connecting said piston chamber with the atmosphere, and a thermostatically controlled valve cooperating with said port for controlling the degree of vacuum in the piston chamber.

In witness whereof I have hereunto set my hand this 25th day of November, 1916.

LEWIS B. DOMAN.
